CENTRIFUGAL SPEED-LIMIT DEVICE.

1,231,586.

Specification of Letters Patent.

Patented July 3, 1917.

Application filed February 1, 1912. Serial No. 674,303.

To all whom it may concern:

Be it known that I, WILLIAM H. Foot, a subject of the King of Great Britain, and a resident of Wilkinsburg, in the county of Allegheny and State of Pennsylvania, have invented a new and useful Improvement in Centrifugal Speed-Limit Devices, of which the following is a specification:

My invention relates to centrifugal speed-limit devices and it has special reference to devices of this general class that are employed in connection with rotary converters and other types of dynamo-electric machines; for the purpose of automatically preventing excessive speeds.

The object of my invention is to provide a device of the above-indicated character that shall be simple, inexpensive and durable in construction and effective and reliable in operation, and be particularly adapted to effect a positive operation of a switching device with which it is associated.

In the prior art, centrifugal speed-limit devices of this general class have been employed for the purpose hereinbefore specified, but, usually, the automatic tripping portions of the devices have been constructed and operated in substantially the manner of engine shaft governors that are adapted for speed-regulation and in which the positions of the centrifugally actuated arms are dependent upon variations in speed. Furthermore, the striking engagements of the arms and the pawls or latches of the switching devices have been effected at the ends of said arms. Thus, the centrifugally-actuated arms usually delivered a series of rapid and light blows to the switching members prior to their final release, and the tripping actions were also unreliable, by reason of the fact that the engagement of the centrifugally-actuated arms and the switch members were effected at points which required the minimum amount of resistance to overcome the torque due to centrifugal force.

According to my present invention, I provide a speed-limit device which is so constructed as to avoid the objections hereinbefore mentioned and to secure reliability, uniformity and positiveness in its operation. The tripping portion of the device embodied in my invention comprises a pivotally mounted member which is provided with a weighted end portion and a striking or engaging

portion located substantially at the center of percussion of the member.

Furthermore, an extension of said member projects beyond its pivotal support and is engaged by a spring which acts in opposition to the centrifugal force exerted upon the weighted portion of the arm until a predetermined speed is reached when the spring acts with decreasing effect. By reason of this construction, the weighted arm is moved quickly from its initial inner position to its outer position, and the engagement of the striking portion of the pivoted arm and the coöperating switch member is effected at approximately the center of percussion of said arm, so that the switching device is positively actuated by a single blow.

My invention may best be understood by reference to the accompanying drawing, in which Figure 1 is an end view, partially in section, of a speed-limit device constructed in accordance with my invention. Fig. 2 is a view, in side elevation, of the tripping portion of the device shown in Fig. 1, and Fig. 3 is a sectional view, taken along the line III—III of Fig. 1, showing the arrangement of the coöperating contact members of the switching portion of the device when the switch is closed.

Referring to the drawing, the apparatus shown comprises, in general, a tripping device 1 and a switching device 2, said tripping device being fixed to a rotatable shaft 3, and comprising a main body member 4, and a pivotally mounted spring controlled member 5, while the switching device 2 is suitably mounted in coöperative relationship to the tripping device 1, and comprises a containing box or casing 7, a switch member 8, a spring 9 and stationary contact terminals 10.

The main body member 4 is of cylindrical form and is secured to the shaft 3 and provided with a projecting peripheral flange 11, having an opening 12 therein to permit the outward movement of the arm 5, as will be hereinafter set forth. The member 5 is pivotally mounted upon a pin 13 and is provided, at its free end, with a weighted portion 14, while an extension member 15 projects slightly beyond its pivotal support. Furthermore, an engaging or striking member 16 forms an integral part of the arm 5 and is located at substantially the center of percussion of said arm.

The extension 15 is provided with a projecting portion 17, which serves as a stop to engage the peripheral flange 11 and prevent the weighted portion 14 of the arm 5 from 5 engaging the shaft 3. The extension 15 is bifurcated and one end of a guide member 18 is pivotally connected between the arms 19 thereof. The other end of said guide member projects loosely through a hollow 10 plug member 20 which is screwed into an opening 21 that is provided in a lug 22 which constitutes a part of the main body member 4. Surrounding the guide member 18 is a helical spring 23 which engages the 15 extension 15 and the inner end of the plug 20, said spring serving to oppose the outward movement of the arm 5. The plug 20 is provided with a slot 24 into which a suitable implement (not shown) may be inserted, for the purpose of adjusting the compression of the spring 18, whereby the tripping device may be set to operate at any predetermined desired speed, as will be readily understood.

25 The box or casing 7 is suitably secured to a lug 25 which may form a part of a bearing or pedestal member 26 by means of which the shaft 3 is supported in the usual manner, and the switch member 8 is pivotally mounted on a shaft 27 that is carried by a bracket member 28, forming a part of the casing 7. The upper portion of the switch member 8 constitutes a dog 29 and is disposed in the path of the striking member 16 when the arm 5 is in its outer position. The lower portion 30 is provided with an insulating block 31 to which is secured a bridging movable contact member 32 that is adapted to coöperate with a plurality of 30 stationary contact terminals 10 which are suitably secured in position upon an insulating block 34, the latter being attached to the casing 7. The contact terminals 10 are respectively connected to a plurality of conductors 35.

Inasmuch as the coöperating stationary and movable contact members 10 and 32 form no part of my present invention, except as they constitute useful elements in an 50 operative combination, no detailed description of the same is deemed necessary, it being understood that contact members of any suitable construction may be employed.

The spring 9 is connected between the 55 upper end of the dog 29 and the outer end of a supporting bracket 36 and is so located, with respect to the switch member 8, that said switch member is normally maintained in approximately its dead center position, 60 although actually slightly overset, as clearly shown in Fig. 1. A screw 37 projects through the casing 7 to engage the lower end 30 of the switch member 8 and is adjustable in order to determine the set position of the switching device.

Assuming the shaft 3, to which the tripping device 1 is secured, to be rotating at a constantly increasing speed and that the various parts of the apparatus occupy the positions shown in full lines in Fig. 1, the 70 operation of the device is as follows:

Below the critical speed for which the device is adjusted, the spring 23 acts upon the extension member 15 in opposition to the action of the centrifugal force produced by 75 the rotation of the arm 5 to maintain said arm in its initial inner position. When such predetermined speed is attained that the torque, due to the centrifugal force on the arm 5, predominates over the torque produced by the spring 23, the arm 5 is suddenly and positively thrown to its full outer position, indicated in dotted lines. No intermediate position can be maintained for the reason that when the arm 5 begins to 80 move outwardly, the torque about the pivotal support 13, due to centrifugal force, increases, while that due to the spring 23 decreases as the axis of the spring more nearly parallels a line drawn between the fixed 90 points 13 and 20, so that the resultant force acting on the arm 5 is constantly increasing, thereby causing the arm 5 to be thrown to its full outer position and preventing any intermediate positions.

When the arm 5 is in its outer position, the striking member 16 is brought into the path of the dog 29 and an engagement between said members 16 effected. Inasmuch as the striking member 16 is located at approximately the center of percussion of the arm 5, a positive and effective blow is delivered to the dog 29, thereby forcing the switch member 8 beyond its dead center position, after which it is actuated in a clockwise direction with a quick movement by means of the spring 9, to effect a rapid and positive closure of the coöperating switch members 32 and 10.

Obviously, it is not essential that the coöperating switch members 32 and 10 be closed through the agency of the automatic tripping device, as, under certain conditions, it may be expedient to arrange the apparatus in such manner as to effect the separation of 115 said switch members.

By a series of experimental tests, I have found that the speed-limit device constituting my invention may be accurately adjusted to any desired speed to operate with 120 reliability, uniformity and positiveness, and I have further determined that when the speed decreases to a predetermined value, the arm 5 is moved back into its initial position with a quick movement.

In order to reset the switching device 2 after the same has been actuated by the tripping device 1 in the manner just described, it is only necessary to force the switch member 8 into its normal set position, which may 125

be done by the operator without removing the cover (not shown) of the casing 7.

Although I have shown and described my invention as embodying specific structural details and arrangement and location of parts, it will be understood that many modifications may be effected therein without departing from the spirit and scope of my invention, and I desire that only such limitations shall be imposed as are indicated in the appended claims.

I claim as my invention:

1. The combination with a rotatable shaft, of a centrifugal operating device carried thereby comprising a base plate provided with an annular flange having a peripheral opening, a weighted arm pivotally mounted on said base plate within said flange, a striking portion integral with said arm and located adjacent to its pivotal support and to said peripheral opening, the said striking portion being adapted to move outward through said opening and to project beyond the outer periphery of said flange, under the influence of centrifugal force.

2. The combination with a rotatable shaft, of a centrifugal operating device carried thereby comprising a base plate provided with an annular flange having a peripheral opening, a weighted arm pivotally mounted on said base plate within said flange, a

striking portion integral with said arm and located at substantially the center of percussion of said arm and adjacent to said peripheral opening, the said striking portion being adapted to move outward through said opening and to project beyond the outer periphery of said flange, under the influence of centrifugal force.

3. A centrifugal device comprising a rotatable member, a pivotally mounted arm associated therewith and having a weighted portion at its free end, a bifurcated extension projecting beyond the pivotal support of said arm, a guide member pivotally connected between the arms of said extension and projecting loosely into an apertured plug member threaded into a portion of said rotatable member and a spring surrounding said guide member and engaging said extension and said plug to oppose the action of centrifugal force on said arm, the tension of said spring being determined by the position of said threaded plug member.

In testimony whereof, I have hereunto subscribed my name this 17th day of Jan., 1912.

WILLIAM H. FOOT.
